Int. Cl. A47b 53/02; B61b 13/00

ABSTRACT OF THE DISCLOSURE

A carriage to provide rolling support for shelving or cabinet units of movable-stack type. The carriage is a rectangular angle-iron frame whose cross-members carry load and guide wheels arranged to run along the rectangular rails. The cabinet or shelving rests on top of the carriage and has a handle on one end panel for manually rolling the cabinet or shelving unit along the rails.

This invention relates to a carriage to provide rolling support for a cabinet or shelving unit of the mobile type. Such units are used in libraries, offices, and storage rooms in order to conserve space, particularly for "dead" storage or other situations where access is required relatively infrequently. The units can be stacked abutting face to face, except for a single aisle space. When access is desired at a particular location along the shelves, the unit or units beyond the desired access aisle are merely rolled away, opening the aisle at the desired location. In order that the units may be kept in alignment as they are rolled back and forth it is generally convenient to support the units on rails or tracks set on or in the floor.

Mobile shelving units for a library, file or storage room may typically be 8, 10, 12 feet or more in width, 7 to 8 feet in height, and up to 3 feet in double-compartment depth. Manifestly such a unit will be extremely heavy when fully loaded with books, files, apparatus, or machine parts stored therein. For the sake of economy, and to minimize problems of alignment and guidance, it is desirable to employ as few load wheels as possible, usually 4 to 6, according to the width of the unit. This necessitates accommodating substantial concentrations of load at the wheel attachments.

Various designs have heretofore been proposed for mobile shelving, generally involving special shelving-base construction in order to provide for mounting the load wheels and guidance means. The usual practice in prior units has been to provide the cabinets or shelving units with a modified, reinforced base frame for mounting the load wheels and guidance devices. Despite rather elaborate and costly such arrangements, prior units have generally been susceptible to sagging and buckling effects, due to load concentrations at the wheel mounts, such as to cause excessive friction, binding, or other conditions which result in excessive drag, particularly with large, heavily loaded units, to the extent of precluding manual locomotion within the capabilities of a single attendant, often female. Therefore, prior designers have resorted to power propulsion means, with the necessary drives, controls, and other expensive, elaborate provisions, which often involve first cost and maintenance expense beyond the reach of many prospective users. The couplings, drives and operating mechanisms also require considerable space, usually involving a sacrifice of the storage space itself, or costly special floor construction to accommodate the several mechanisms.

It is an object of this invention to provide a mobile shelving carriage which will accommodate and support heavy shelf units in position for free rolling along tracks or rails, which yet is light, compact, inexpensive to manu-

2

facture, and requires little maintenance or operating expense.

It is a further object of this invention to provide a carriage affording adequate mobile support for a shelf unit of size, style, and construction substantially suitable for comparable shelving units free-standing in stationary position on a floor.

It is still a further object of this invention to provide a mobile shelving carriage which includes simple, inexpensive mounting arrangements for load and guide wheels of conventional and readily available types and sizes.

Another object of this invention is to provide, in association with a mobile shelving carriage, a load wheel and guidance arrangement which can be used with a simple rectangular track, all so constructed and arranged that special floor construction is obviated, yet without significantly sacrificing storage space.

Other objects and advantages of the invention will be apparent from the ensuing description read in association with the accompanying drawings, wherein:

FIG. 1 is a perspective view of a mobile shelving stack, units of which are equipped with carriages according to this invention;

FIG. 2 is a top plan view of the novel carriage of this invention in position on the rails;

FIG. 3 is a side view of one corner of the carriage taken on line 3—3 of FIG. 2, showing the load and guide wheels and mounting thereof on the carriage frame;

FIG. 4 is a bottom plan view of the carriage corner portion shown in FIG. 3, taken on line 4—4 of FIG. 3; and

FIG. 5 is a detail of a load-wheel axle.

Referring first to FIG. 1, reference numeral 10 indicates a mobile shelf unit having an end panel 11 with a handle 12 fastened to the panel. Three such shelving units are shown in the view, but obviously any number of such units may comprise a stack series, according to the space available. While the drawings show mobile units of identical size, a series may include units of various depths, in such arrangement as provides the maximum usable storage space in the given room. For example, a library storage room may house some sets of large books and sets of small books, the former of which may require deep shelf units while the latter only requires shallow units. In any case, the series can be arranged in such multiples as to best utilize the space allotted.

Units 13, 14 are single depth stationary units, or caps, which may be used to close the stack against the walls or other boundary lines. For the sake of convenience and appearance, the closure units 13, 14 are preferably of the same general design as the mobile units 10, providing an additional complete storage unit on each end aisle. For long stacks it may be desirable to include a double depth stationary unit at the center of the stack and provide for two aisles, thus reducing the number of mobile units which must be rolled to open terminal aisles.

The construction of the novel carriage is best seen in FIGS. 2, 3, and 4. From FIG. 2 it will be seen that the carriage frame comprises a pair of parallel, spaced sill members 15, 16 tied at each end with a spaced pair of cross-members 17, 18 at the left end and 19, 20 at the right end, the cross-members nesting in the sill angles. The lengths of the sill members 15, 16 are substantially equal to the base width of the shelving or cabinet unit to be supported and the members are so spaced that the horizontal flanges 21, 22 of sill members 15, 16 underlie the base framing of the cabinet or shelving unit providing full width support. While various structural shapes or combinations thereof may be used to construct the frame, the drawings show a preferred form, in which all the members are made of the same angle-iron section, a typical selection of which for average loading would be $1\frac{1}{4} \times 1\frac{1}{4} \times \frac{3}{16}$

angle. As best seen in FIGS. 2 and 4, sill flanges 21 and 22 overlie vertical cross-member flanges 23, 24, 25 and 26. The pieces are welded together at the corners formed by the flange intersects, as best seen at 27, 28 in FIG. 3 and 29, 30 in FIG. 4.

For very wide, heavy units of 10 to 12 feet or more in width, it will usually be desirable to incorporate intermediate cross-members 31, 32, FIG. 2, in the carriage, to minimize sag and keep stresses in wheels and mountings within safe limits, without increasing the overall height of the carriage, thus permitting maximum utilization of basic frame materials and components.

Each pair of cross-members 17, 18 and 19, 20 is spaced apart, the span between the spaces being equal to the span between rails 33 and 34. A load wheel 35 is supported between cross-members at or near each corner of the carriage, the arrangement being best seen in FIG. 3, which is illustrative of all wheel locations.

The space between vertical flanges 25, 26 of the cross angles is just slightly greater than the width of rail 34. The load-wheel rim width is about the same as the width of rail 34, thus providing full width load-bearing contact. Load wheel 35 is mounted on a fixed axle 36 extending between flanges 25 and 26. The axle 36 may conveniently be a modified cap screw, as seen in FIG. 5, having a head 37, a journal 38, and threaded end 39, the journal 38 having a length approximately equal to the width of the wheel 35 journaled thereon.

Referring now to FIGS. 3 and 4, the guide wheels 40 and 41 depend from horizontal flanges 42 and 43 in position with their rims separated just slightly more than the width of rail 34. Guide wheels 40 and 41 are journaled on fixed axles 44 and 45, similar to the load wheel axle 36, except having a shorter journal. The guide wheels are narrower than the load wheels, since the guide wheels are called upon only to sustain horizontal loading, which is generally nominal in value. Where necessary for assembly clearance purposes, as in the particular example here shown, guide wheels 40 and 41 may be inset slightly from load wheel axle 36, along flanges 42 and 43, obviating interferences, as for example between heads and ends. However, as a general rule, the guide wheels are positioned as near the outer ends of the cross-members 19 and 20 as practicable, to provide the greatest guidance span cross-wise of the carriage and thus to minimize weaving of the unit as it is rolled along the rails.

As seen in FIG. 3, rail 34 may be of solid rectangular cross-section, made of hardwood, for example, with a steel facing 46 across the top to serve as bearing surface for the load wheels and steel side facings 47 and 48 opposed to the guide wheels.

For the sake of maximum efficiency, convenience, and economy, ball or roller bearing machine units are used for both the load and guide wheels. Where carriage assemblies are to be made in relatively small quantities at any one time, a single size and style of machine unit may be used for the wheels throughout. As shown, single bearing machine units serve for the guide wheels 40 and 41, while two bearing machine units 35a, face to face, constitute load wheels 35, providing the necessary rim width and radial-load bearing capacity for this service. For average service conditions, a bearing machine unit of 1½" O.D. x ½" face is suitable. Where large quantities of identical or closely similar mobile units are to be manufactured at one time, economy of such manufacture may dictate selection of wheels specifically sized for the particular load conditions, without regard to interchangeability, for example by using suitable double width bearing machine units, or the like, as load wheels.

Assembly of the carriage and cabinet or shelving unit can usually best be done upon installation. The tracks 33, 34 are laid on the floor and the carriage positioned on the rails, while the rails are temporarily fixed, the carriage being then run back and forth, to check straightness and parallelism of the rails. When rail positions are thus veri-

fied, the rails may be permanently fastened down. The cabinet or shelf unit is then set in position on the carriage, whose sills are provided with holes 49, FIG. 2, to receive cap screws or self-tapping screws 50, passing through the bottom rail 51 of unit 10, FIG. 1, to preclude shifting or tipping of the cabinet or shelf unit when being moved. The remainder of the carriages and cabinets or shelf units are then assembled in like manner in their respective positions on the rails, completing the installation. It will be seen that by virtue of the carriages being self-contained units, assembly and installation are considerably simplified, as compared with prior designs, in which the carriage is virtually an integral part of the unit. Furthermore, the carriage, having a steel framework, is not subject to the warpage, sagging or buckling and consequent drag to which conventionally built mobile shelving units are generally susceptible, particularly wooden ones. Units made according to this invention remain free rolling under heavy loads with minimum maintenance. Permanently greased wheel bearings may be used, so that the installation will usually be maintenance free. With mobile unit stacks constructed according to this invention, one or more large heavy units can easily be rolled by one female attendant or user, thus facilitating access to any section of the stacks by persons usually attending or using same. For example, with the stack in the position of FIG. 1, it will usually be feasible for the attendant to roll all three units 10 forward to open the rearmost aisle for access in that section of the stack.

While I have described one form of the invention for the purpose of illustration, it will be understood that those skilled in the art will be enabled thereby to design modifications and variations of the invention without departing from the spirit and scope of the appended claims.

What I claim and desire to secure by Letters Patent is:

1. A carriage for a mobile shelving unit, comprising: a frame having a pair of structural metal sills and at least two pairs of structural metal cross-members, one pair of said cross-members being fixed transversely of said sills near each end thereof, load wheels supported upon said cross-members near the corners of said frame, said load wheels being journaled on horizontal axles, and guide wheels suspended from said frame, said guide wheels being journaled on vertical axles, said carriage being fully self-contained, whereby to sustain loads imposed by the weight of said unit at said load wheels independently of said unit, when said unit is supported on said carriage.
2. A carriage according to claim 1, wherein said sills and said cross-members consist of angle, ends of said cross-members being nested in the angles of said sills.
3. A carriage according to claim 1, wherein the individual cross-members of each end pair are spaced from each other, said load wheels being between said individual members.
4. A carriage for a mobile shelving unit, or the like, comprising: a frame having a pair of structural metal sills and at least two pairs of structural metal cross-members, one pair of said cross-members being fixed transversely of said sills near each end thereof, load wheels supported upon said cross-members near the corners of said frame, said load wheels being journaled on horizontal axles, and guide wheels suspended from said frame, said guide wheels being journaled on vertical axles, said sills and said cross-members consisting of angles, ends of said cross-members being nested in the angles of said sills, the individual cross-members of each pair being spaced from each other, said load wheels being between said individual members, said individual cross-members further being structural angles, each said individual cross-member having a vertical leg and a horizontal leg, said load wheels being supported upon opposed vertical legs, said guide wheels being suspended from said horizontal legs.
5. A carriage according to claim 4, wherein one of

said load wheels is located near each corner of said frame, a pair of said guide wheels being adjacent to each said load wheel, the guide wheels of each said pair being spaced along said frame on opposite sides of an adjacent load wheel.

6. A carriage according to claim 4, wherein said load wheel axles extend between said opposed vertical legs of said cross-members.

7. A carriage according to claim 2, further including receptor means on said sills adapted for affixing said unit upon said carriage.

8. A carriage according to claim 7, wherein outline dimensions of said carriage are substantially the same as

outline dimensions of said unit to be supported upon said carriage.
